SEAL PROTECTOR

William P. Robinson, Compton, Calif., assignor to H. C. Smith Oil Tool Co., Compton, Calif., a corporation of California

Application February 28, 1958, Serial No. 718,266

4 Claims. (Cl. 308—187.1)

This invention relates to a protecting means for protecting seals and packings for bearings between vertically disposed rotary shafts and surrounding sleeves in abrasive environments.

Explanatory of the present invention, it has heretofore been proposed to drill water, oil, and gas wells by an apparatus wherein the drill pipe is held stationary or against rotation in the well. Near the bottom of the drill pipe there is a hydraulically operable motor or turbine which is motivated or propelled by the circulation fluid that is pumped down the drill pipe. This motor or turbine in turn rotates a vertically disposed shaft within the bottom of the drill pipe and this shaft, in turn, drives or rotates the bit used to drill the well. There are a number of advantages to be derived from such an apparatus, an important one of which is the ability to rotate the bit at comparatively high speeds.

It is necessary to provide some form of bearing between the rotating shaft and the surrounding lower end of the stationary drill pipe, and such a bearing should not only be well lubricated with a lubricant maintained at a pressure of the circulation fluid in the vicinity of the bearing, but the bearing should be also protected against ingress of abrasive particles carried by the circulation fluid. If packing seals are provided at the top and bottom of the bearing to confine the lubricant and prevent ingress of abrasive particles to the bearing, these packing seals in turn are subject to the abrasive particles carried by the circulation fluid and consequently quickly become worn to such an extent as to leak and allow the abrasive particles to enter the bearing.

It is a primary object of the present invention to provide a means for protecting these packing seals from the abrasive particles in the circulation fluid and in this manner if the packing seals can be protected from abrasion the seals will function properly to prevent ingress of abrasive particles to the bearing and thus keep the lubricant fed to the bearing in a clean condition. In this manner, the life of the bearing may be materially prolonged.

With the foregoing and other objects in view, which will be made manifest in the following detailed description and specifically pointed out in the appended claims, reference is had to the accompanying drawings for an illustrative embodiment of the invention, wherein:

Figure 1 is a vertical section through a vertically rotating shaft and through its surrounding sleeve or drill pipe illustrating a bearing between the shaft and sleeve as being protected and lubricated in accordance with the present invention; and

Fig. 2 is a partial view in vertical section showing a portion of Fig. 1 on an enlarged scale.

Referring to the accompanying drawing wherein similar reference characters designate similar parts throughout, 10 indicates the lower end of a stationary or non-rotating drill pipe within which there is a vertically disposed shaft 11 which is rotated about its vertical axis by any suitable source of motive power, such as a hydraulically

2

driven turbine that is driven by the circulation fluid that is pumped down the drill pipe. Between the shaft 11 and the drill pipe 10 there is an anti-friction bearing illustrated as consisting of a ball thrust bearing 12 above and below which there are radial roller bearings 13 and 14. The details of construction of the particular anti-friction bearing are unimportant insofar as the present invention is concerned and the nature of the anti-friction bearing may vary as to design to a wide extent.

10 That portion of the shaft 11 which extends through the bearing is hollow as indicated at 15 with ports 16 arranged near its top so that the circulation fluid, after passing through the turbine may pass downwardly through the hollow shaft and be discharged through the bit. 17

15 indicates a sub drill collar or it may comprise the top of the bit body itself. It is mounted on the lower end of the shaft 11 so as to be forcibly rotated thereby.

As above explained, the problem is to keep the bearing supplied with clean lubricant preferably at a pressure of the circulation fluid in the vicinity of the bearing and to prevent ingress of abrasive particles from the circulation fluid into the bearing. To this end, an inner sleeve 18 is disposed between the hollow portion of the shaft 11 and the surrounding sleeve or cylinder 25 provided by the stationary or non-rotatable drill pipe 10. This sleeve defines two cylindrical chambers one of which is indicated at 19 and the other of which is indicated at 20. The latter chamber constitutes a reservoir for lubricant. A packing seal 21 is arranged between the hollow portion of the shaft 11 and the sleeve 18. This packing seal is tightened such as by a nut 22 to form a close wiping contact between the exterior of the rotating shaft 11 and the interior of the inner sleeve 18 which is rigid with the stationary or non-rotatable drill pipe 10.

30 A second inner sleeve 23 is threaded or otherwise secured to the lower end of the stationary drill pipe 10 and extends downwardly about the lower end of the hollow portion of shaft 11. This sleeve houses a lower packing seal 24 which can be tightened such as by a nut 25. The lower packing seal 24 provides a good wiping contact between the exterior of the rotary shaft 11 and the interior of the sleeve 23 which is rigid with the stationary drill pipe. The sub drill collar or bit body 17 extends upwardly around the lower end of the inner sleeve 23 to define a chamber 26 open against the bottom of the lower seal. Both of the chambers 19 and 26 may be regarded as open-topped chambers which have downwardly extending lips 27 and 28 near their tops. Both chambers are 40 partially filled with a heavy dense liquid that is emissible with the circulation fluid. An excellent liquid for this purpose is mercury, the mercury being indicated at 29 and 30 in the two chambers.

45 The top of the lubricant reservoir is closed by a confining ring 31 through which there are ports 32 which conduct the pressure of the circulation fluid to the top of an annular piston 33 which is vertically movable in the reservoir 20. This annular piston may be equipped with suitable packing rings or the equivalent. The pressure of the circulation fluid between the shaft 11 and the interior of drill pipe 10 is transmitted through the ports 32 to the top of the piston 33 and is transmitted by the piston to the lubricant in the reservoir 20. The lubricant is forced from the reservoir 20 into the bearing 55 through ports 34 so that the pressure of the lubricant in the bearing is always maintained at substantially outside pressure. The circulation fluid that is descending through the drill pipe 10 after having passed through the hollow portion 15 of the shaft after entering through the ports 16. The circulation fluid, however, is also effective on the tops of the two mercury columns 29 and 30 as the chambers which

60

65

70

contain these mercury columns have open tops. The descending circulation fluid can of course enter the top of chamber 19 and the discharged circulation fluid rising on the outside of the drill pipe 10 can enter the top of chamber 26. Any abrasive particles carried by the circulation fluid tending to settle in the two chambers 19 and 26 encounter the tops of the mercury columns and due to the high density of the mercury these particles will merely float on top of the mercury columns. They will consequently not settle through the mercury to contact the seals 21 and 24 and these packing seals are consequently kept free of abrasive particles that may be in the circulation fluid. The life of the seals is consequently materially prolonged as they are kept quite clean. As the seals in turn prevent ingress of abrasive particles to the bearing and confine the lubricant forced into the bearing from the reservoir 29, the life of the bearing is materially prolonged.

The downwardly directed lips 27 and 28 serve to confine the mercury in the chambers 19 and 26 and depending upon the volume of mercury in the chambers, these lips may serve to keep the mercury in the chambers even though the entire structure illustrated is positioned horizontally in the course of transporting the structure to and from the well site.

From the above-described construction it will be appreciated that where a bearing is disposed between a rotating shaft and a surrounding stationary sleeve such as the stationary drill pipe 10 and there is an abrasive environment, that it is possible to protect the bearing from wear due to abrasive particles by arranging packing sleeves above and below the bearing which, in turn, are protected against abrasion by mercury seals above the uppermost packing seal and against the bottom of the lowermost packing seal.

In the foregoing description the shaft 11 and its associated structure has been described as being vertically disposed due to the fact that this is the normal position assumed by these parts in the course of ordinary well drilling. Frequently contracts require the drilling of an oil well to be maintained within 3° of vertical. There are, however, numerous situations wherein slant-hole drilling is performed wherein the axis of the well bore may depart from the vertical as high as 70°. The present invention is susceptible of being used in slant-hole drilling as well as in vertical drilling, it being merely necessary to lengthen the chambers 19 and 26 sufficiently to keep the mercury confined therein even though the axis of the device may be steeply slanted with respect to the vertical.

Various changes may be made in the details of construction without departing from the spirit and scope of the invention as defined by the appended claims.

I claim:

1. In combination, a shaft rotatable within a surrounding sleeve, a bearing between the shaft and sleeve, seals above and below the bearing, means defining a chamber on top of the upper seal, means defining a chamber against the bottom of the lower seal, both of said chambers having open tops and having mercury disposed therein against the seals.

2. In combination, a shaft rotatable within a surrounding sleeve, a bearing between the shaft and sleeve, seals above and below the bearing, means defining a chamber on top of the upper seal, means defining a chamber against the bottom of the lower seal, both of said chambers having open tops and having mercury disposed therein against the seals, there being downwardly directed lips adjacent the open tops of the chambers.

3. In combination, a shaft rotatable within a surrounding sleeve, a bearing between the shaft and sleeve, seals above and below the bearing, means defining a chamber on top of the upper seal, means defining a chamber against the bottom of the lower seal, both of said chambers having open tops and having mercury disposed therein against the seals, a lubricant reservoir adjacent the bearing and in communication therewith, and means for transmitting pressure externally of the reservoir to the lubricant therein.

4. In combination, a shaft rotatable within a surrounding sleeve, a bearing between the shaft and sleeve, seals above and below the bearing, means defining a chamber on top of the upper seal, means defining a chamber against the bottom of the lower seal, both of said chambers having open tops and having mercury disposed therein against the seals, a lubricant reservoir adjacent the bearing and in communication therewith, and a balancing piston reciprocable in the reservoir for transmitting pressure to the lubricant therein.
